UNITED STATES PATENT OFFICE

HARRY S. WALTHERS, OF BELOIT, WISCONSIN, ASSIGNOR TO YATES-AMERICAN MACHINE COMPANY, OF BELOIT, WISCONSIN, A CORPORATION OF DELAWARE

CUTTER HEAD

Application filed July 22, 1929. Serial No. 379,961.

This invention is concerned with cutter heads of the type designed to receive a plurality of knife carriers, and has for its object the provision of a novel cutter head assembly which is extremely simple, compact, rigid, durable, and inexpensive to manufacture.

While the foregoing statement is indicative in a general way of the nature of the invention, other more specific objects and advantages will be apparent upon a full understanding of the structural features of the various parts of the improved assembly.

One form of the invention is presented herein for the purpose of exemplification but it will of course be appreciated that the invention is susceptible of embodiment in other modified structural forms coming equally within the scope of the appended claims.

In the accompanying drawings:

Fig. 1 is an end view of a cutter head and knife carrier assembly constructed in accordance with the invention; and

Fig. 2 is a face view of the assembly, with portions broken away to illustrate more clearly the interior construction.

As will be observed in the drawings, the assembly includes a one-piece cutter head 10 which has a cylindrical bore 11 and a cylindrical outer face 12 through which T-shaped slots 13 are cut transversely at regular intervals. The head 10 is adapted to receive a plurality of knife carriers 14 which have concave inner faces 15 which are adapted to fit snugly against the cylindrical face 12 of the head and transverse ribs 16 intermediate the front and rear edges of the concave faces 15 which are adapted to fit within the narrow outer portions 17 of the slots 13. The carriers 14 are provided with apertures 18 at the locations of the ribs, and bolts 19 are adapted to extend through the apertures and engage with nuts 20 on the outer faces of the carriers, with the heads 21 of the bolts within the wide inner portions 22 of the slots 13 in interlocked engagement with the shoulders 23 formed at the sides of the slots. The outer faces of the carriers are preferably flat and are normal to the curvature of the inner faces at the locations of the transverse ribs, thereby resulting in proportionately thick

and consequently strong heels on the carriers while at the same time materially reducing the peripheral weight in the head when fully assembled.

The curvature of the inner faces 15 of the carriers is preferably on a slightly shorter radius than the curvature of the outer face 12 of the head, in order to cause the carriers to bear against the head along the front and rear edges only. The interlocking association of the ribs 16 with the sides of the outer portions 17 of the slots 13 prevents any canting of the carriers, while the clamping action of the bolts 19 and carrier-securing nuts 20 effectively precludes any axial displacement of the carriers.

The cutter head of the invention, by reason of its simple and compact form, is easy to manufacture, requires but a few operations in its formation, is exceedingly strong and permits of secure attachment of the carriers with the attaching means subject only to radially applied stresses. The slight difference between the degrees of curvature of the opposed faces of the head and carriers insures a snug fit even though a small amount of foreign matter is present on such surfaces.

Knives of any description may be attached to outwardly projecting flanges 24 on the carriers, which flanges may be apertured at 25 for the reception of attaching bolts.

I claim:

1. A cylindrical cutter head having transverse T slots therein, a plurality of inwardly concave knife carriers of slightly less radius than the head having transverse ribs thereon for arrangement about the head in snug complementary interfitting relation thereto with the ribs positioned in the outer narrow portions of the slots, and headed bolts in the wide portions of the slots projecting outwardly through apertures in the ribs for holding the carriers against radial displacement.

2. A cylindrical cutter head having transverse T slots therein, a plurality of inwardly concave and outwardly flat knife carriers having transverse ribs on the inner concave faces thereof, said carriers being of progressively increasing thickness from the ribs

rearwardly toward the heels thereof and being arranged about the head in snug complementary interfitting relation thereto with the ribs positioned in the outer narrow portions 5 of the slots, headed bolts in the wide portions of the slots projecting outwardly through apertures in the ribs, and nuts mounted on the outer ends of the bolts in engagement with the outer flat faces of the carriers for holding 10 the latter against radial displacement.

3. A knife carrier for application to a cylindrical transversely slotted cutter head, characterized by a concave inner face for complementary engagement with the outer 15 face of the head and a substantially flat outer face for engagement with suitable holding means, and a transverse rib on the curved inner face of the carrier intermediate the front and rear portions thereof for interfitting association with one of the slots in the outer 20 face of the head, said carrier being of progressively increasing thickness from the rib toward the rear portion of the carrier.

In witness whereof I have hereunto sub-
25 scribed my name.

HARRY S. WALTHERS.
